UNITED STATES PATENT OFFICE.

GEORGE M. MILLER, OF LANCASTER, PENNSYLVANIA, ASSIGNOR TO S. R. SLAYMAKER,
OF LANCASTER, PENNSYLVANIA, TRADING AS SLAYMAKER LOCK COMPANY.

AUTO-LOCK.

1,261,423.

Specification of Letters Patent. Patented Apr. 2, 1918.

Application filed April 25, 1917. Serial No. 164,412.

To all whom it may concern:

Be it known that I, GEORGE M. MILLER, a citizen of the United States, residing at Lancaster, in the county of Lancaster and State of Pennsylvania, have invented certain new and useful Improvements in Auto-Locks; and I do hereby declare the following to be a full, clear, and exact description of the invention, such as will enable others skilled in the art to which it appertains to make and use the same.

This invention relates to locks, and more particularly to a safety lock especially designed and adapted to be used for locking either the steering wheel or the brake and gear levers of an automobile, for protection against theft when the machine is left unattended upon the streets or roads. The invention may be used for other purposes, as an ordinary locking means, although it is designed more particularly for use as a safety lock for automobiles.

Automobile locks as ordinarily constructed have caused a great deal of annoyance and trouble, due to the fact that no means are provided to prevent the inexpert or careless user from inserting the shackle in the wrong end of the case containing the lock mechanism, that is, with the key-end of the case foremost, and when the shackle is inserted at the key-end and the lock moved close enough to prevent the removal or insertion of the key used to disengage the interior locking mechanism, it is necessary to destroy or break the lock in order to remove it from the shackle and release the steering wheel or other part of the machine which is locked.

The primary object of my invention is to provide a device of the character referred to in which the lock or casing member in which the locking mechanism is inclosed can be applied to the shackle at the end opposite the key-end only, so that the lock may not be inadvertently or carelessly applied to the shackle with the key-end foremost, as so frequently occurs in using auto locks as heretofore ordinarily constructed, with the result stated. Other objects are to provide a safety lock of the character referred to which shall be simple in construction, inexpensive in manufacture and adapted to be quickly and readily adjusted to use in a few seconds when desired.

The invention will first be hereinafter more particularly described, with reference to the accompanying drawings, which are to be taken as a part of this specification, and then pointed out in the claims at the end of the description.

In the drawings, Figure 1 is a side elevation of a device embodying my invention, showing the shackle and casing inclosing the lock-mechanism disconnected;

Fig. 2 is a side elevation illustrating the lock applied to the shackle; the cover plate of the casing inclosing the locking mechanism being removed to disclose the working parts within the casing;

Fig. 3 is a sectional view taken on the line 3—3 of Fig. 2, looking in the direction of the arrow;

Fig. 4 is an end view of the lock or casing inclosing the locking mechanism; and

Fig. 5 is a detail perspective view of a sliding pawl or dog used to engage the ratchet face of the shackle arm and prevent return movement of the lock; a key inserted therethrough being indicated in dotted lines.

In said drawings, in which the said reference letters are used to denote corresponding parts in different views, the letter A denotes a two-part casing within which may be inclosed any suitable locking device for engagement with the shackle inserted therethrough to prevent removal of the lock without the aid of a key, though a pawl and ratchet device of the form shown is preferred. The casing preferably consists of two oppositely disposed hollow or concave plates a and a' fastened together by bolts or otherwise to form a housing for the lock mechanism. These plates have end walls, as shown, with holes therein at opposite ends formed by semi-circular registering recesses in said end walls arranged in alignment with openings through the casing which provide an uninterrupted passage for the insertion of the shackle arms or prongs of the lock member or shackle B, the extremities of which may protrude through the casing as the latter is pushed along said arms and may be locked at any desired point so as to prevent the lock and shackle from being disconnected until unlocked by the use of a key. The lock member or shackle B is provided with a series of ratchet teeth or

105

notches b on the inner faces of the two arms and also preferably with a lug b^1 at the end of one arm adapted to serve as a guide in applying the lock and as a means to prevent the shackle arms or prongs from entering the openings in the casing should it be attempted to push said casing upon the shackle from the wrong end thereof. To this end a recess a^5 extends through the casing opening into the margin of each of the holes in the opposite end walls of the casing; the recess at one side extending in an opposite direction to the recess at the other side of the casing, so as to provide a passage for the lug b^1 on one of the shackle arms at either side of the casing to enable the shackle arm to pass through or into the opening through the casing at either side thereof but only when the casing is properly applied, that is, when applied at the end opposite or remote from the key-end.

Within the casing may be fitted a pair of sliding bolts or ratchet locking lugs D , each of which is formed with an intermediate aperture d , therethrough, preferably of oblong or approximately oval form, and having an offset portion d^1 at one side thereof, to provide a shoulder for engagement with a key, as clearly shown in Figs. 3 and 5; said pawl also having a beveled tooth or projection d^2 at one end, for engagement with the ratchet teeth or notches in the shackle arm, and a recess d^3 at the other end thereof in which one end of a spring C may be seated. Said spring tends normally to force and hold the pawl in engagement with the notches in the shackle arm when the latter is inserted in the casing. The pawls D are fitted to slide back and forth in suitable guideways or grooves a^2 formed within the casing and are disposed in reverse relation to each other, one at or near one end of the casing and the other at or near the other end thereof; each having its beveled tooth or projection arranged to engage the notches in the adjacent arm of the shackle with its beveled or inclined face facing the inclined faces of the notches in the shackle arm, as more clearly shown in Fig. 2. The springs C may each be fastened at one end to a lug a^3 on the inner side of the casing A , and are preferably coiled around a stud a^4 on the same side of the casing so as to increase the tension of the spring. The free ends of the springs fit respectively within the recesses d^3 of the pawls D , to adapt them to press laterally against said pawls and force the same continuously into engagement with the notched arms of the shackle and thus prevent withdrawal of the casing without using a key. A single pawl may be used engaging one arm only of the shackle, though preferably two are employed, one for each shackle arm. A series of ordinary tumblers E may be seated within a channel

or recess provided therefor within the casing A , and are preferably disposed between the pawl members D with the openings therethrough in alinement with the openings through the pawls. Said tumblers may be so arranged as to adapt a different key to fit different arrangements of the series of tumblers in series, thus making it possible to provide a key of different pitch for each lock. A key F adapted to fit the arranged series of tumblers E may be inserted through the key guide f , through which an opening is formed conforming to the shape of the key; said key guide being annularly grooved to adapt it to be retained by and between the end walls of the plates a and a^4 of the casing which have semi-circular recesses formed therein to adapt them to fit the annular groove in said guide and retain the same therebetween. Said guide is arranged in direct alinement with the intermediate apertures in the sliding dogs D and the tumblers E .

In operation, when the key F is inserted and turned in the proper direction, (to the right as here shown), the body of the key will engage the shoulders d^1 of the dogs D and force the latter out of engagement with the notches in the arms of the shackle, thereby releasing the casing A and permitting it to be pulled off of the shackle; but if the key is turned backward or withdrawn, the springs C will force the dog or dogs back into position where they will again engage the notches in the shackle arms and prevent the removal of the lock. The lock can be applied after removal from the shackle by inserting the prongs of the shackle in the openings through the casing at that end only which is opposite the key-end, for the reason that the dog adjacent said key end normally obstructs the passage through which the prong must enter the casing; the straight edge or flat face of the tooth of the dog being adapted to contact with the flat end of the shackle arm and arrest the movement and prevent the prong from entering at the key-end, though at the other end the beveled edge or face of the dog is presented and by engagement of the end of the prong therewith it will be forced back against the pressure of the spring to allow the prong to enter. Insertion at the wrong or key end is also prevented by the lug b^1 on the other arm of the shackle, which is adapted to strike the end of the casing unless the shackle is properly inserted, in which position the pin on the shackle arm will pass through the recess a^5 and freely through the casing. This auxiliary device, though desirable because of its function as a guide in properly inserting the shackle, might be dispensed with.

Other changes in the details of construction and arrangement of parts might be

made without departing from the spirit and scope of my invention; hence I do not desire to be limited to the specific construction and arrangement shown, which is 5 merely a preferred form.

Having thus described my invention, what I claim as new and desire to secure by Letters Patent is:

1. A lock for automobiles and the like comprising a casing member containing suitable locking mechanism; said casing member having openings extending therethrough to receive the arms of a shackle, and a recess in the margin of each of said openings at the 10 end thereof opposite the key-end, the recess at one side of the casing extending in an opposite direction to the recess at the other side thereof, one of said arms having a ratchet face, means within said casing adapted 15 to engage the ratchet teeth and prevent return movement of the casing, a key-guide at one end of the casing through which a key may be inserted, and a projection on one arm of said shackle adapted to fit one 20 of said recesses when the shackle is properly applied, whereby the insertion of the shackle at the key-end of the casing is prevented.

2. A lock of the class described comprising a casing having locking bolts arranged therein, a shackle having a plurality of arms adapted to slidably extend entirely through said casing, said arms being provided with notches to receive said locking bolts, said locked bolts having beveled ends adapted to 30 permit said arms to slide freely in said casing in one direction, and flat sides adapted to prevent the entrance of said arms in the opposite direction, and means on the shackle and coöperating means on the casing to prevent the insertion of said shackle into said casing from that end of the casing opposite the key-end.

3. An automobile lock comprising a shackle, having two arms, a casing having 45 openings therethrough in which the arms of the shackle may be inserted, one of the shackle arms having a ratchet face, means within said casing adapted to engage said ratchet and prevent the withdrawal of the shackle, a key-guide at one end of the casing through which a key may be inserted for releasing the shackle, and means on said shackle and casing whereby the arms of the shackle cannot be inserted in the openings through the casing when applied at the 50 key-end thereof.

4. A locking device comprising a shackle having two prongs and a casing having openings therethrough to receive said prongs and movable along the same, one of said prongs 60 having a series of notches therein, means within said casing adapted to engage said notches and lock the casing or prongs against backward movement; said casing also having means thereon at one end for inserting a 65 key to release the casing, and means on the shackle and coöperating means on the casing to prevent said prongs from being inserted in said openings at the key-end of the casing.

5. In a lock of the class described the combination with a shackle having arms provided with ratchet notches, a casing provided with shackle arm apertures, a plurality of guides in said casing, locking dogs 70 adapted to slide in said guides transversely of said openings, said dogs having beveled teeth flat faced on the opposite side thereof, a series of tumblers arranged intermediate said guides, a plurality of springs arranged 75 on opposite sides of said tumblers and adapted to normally project said dogs into said shackle arm apertures and prevent the entrance of said arms by contact with the flat faces of said teeth, said dogs and tumblers adapted to receive a key to operate the same.

6. A casing having shackle openings extending therethrough, slidable locking dogs, arranged in said casing and normally projected into said openings and beveled on one face, mechanism operable from one end of the casing for retracting said lugs, a shackle having a plurality of arms, a series of ratchet notches extending longitudinally 95 of said arms and adapted to be progressively engaged by said dogs as the shackle is moved into said casing whereby the shackle is locked against reverse movement and projections on the shackle arms together with 100 means on the casing adapted to prevent entrance of the shackle arms into said casing from that end of the casing toward which the bevels on said locking dogs face.

In testimony whereof I affix my signature 105 in the presence of a witness.

GEORGE M. MILLER.
